UNITED STATES PATENT OFFICE

Patent No. 2,562,089

MAGNETIC TARGET WITH ENVELOPE

Irving H. Fishlove, Chicago, Ill.

Application April 22, 1946, Serial No. 664,073

3 Claims. (Cl. 273—102)

179,031,8

This invention relates to a game apparatus and more particularly to a game apparatus employing magnetic projectiles intended to be thrown against a game board.

One of the objects of my invention is the provision of a game apparatus of the character set forth which will require skill in the successful playing thereof, and which will provide amusement and entertainment for the players, as well as for the persons watching the game being played.

Another object of my invention is the provision of a game apparatus of the character set forth in which a plurality of game indicia may be used interchangeably to permit the playing of a variety of games, using the same basic components, thereby providing a game having a high degree of versatility and increasing the amusement that may be derived from the game apparatus.

A further object of this invention is the provision of a game apparatus of the character described which is simple in construction, attractive in appearance, and which may be manufactured economically.

Other objects and advantages of this invention will be apparent from the following description taken in connection with the accompanying drawings in which:

Fig. 1 is a perspective view of a game apparatus embodying my invention with a portion broken away to show certain details of construction.

Fig. 2 is a vertical cross-sectional view of the device shown in Fig. 1.

Fig. 3 is an elevational view of a detail.

Fig. 4 is a perspective view of a projectile used in playing the game.

Referring to the drawing wherein is shown a preferred embodiment of my invention, the numeral 10 designates, generally, a game board which comprises a flat rectangular panel 11 of magnetically attractive metallic material which may be disposed and supported in an inclined position by a leg 12 hingedly connected, as at 14, to the upper portion of the panel 11.

The panel 11 is adapted to be received in an envelope 15 of a conventional type and to be suitably secured thereon, as with a string 16, which is arranged to be wound around a button member 17 mounted on the flap 19. It is to be understood, however, that the above means for securing the envelope on the panel is merely illustrative of one form and that any other suitable means may be employed.

The envelope 15 may have printed on one or

either of its opposite surfaces or portions of the same surface, characters, symbols, pictures, or any other indicia which may be used in playing the game, such as for example, a bull's-eye target or concentric annular rings or any other desirable game indicia.

Turning now to Fig. 2, it will be seen that the envelope 15 is a rectangular article having a central opening, a guideway, and a playing surface. The guideway is formed by a pair of parallel longitudinal strips of relatively thin metal, which strips are spaced from the outer edges of the envelope 15 and the panel 11, and which strips are bent at their outer ends to receive and hold the projectile 21.

The playing surface 18 is formed by a pair of parallel longitudinal strips of relatively thin metal, which strips are spaced from the outer edges of the envelope 15 and the panel 11, and which strips are bent at their outer ends to receive and hold the projectile 21.

Both of the outer surfaces of the envelope 15 are provided with a layer of magnetic material, such as for example, a thin sheet of Alnico, a commercial alloy of aluminum, nickel, and cobalt, which exhibits magnetic characteristics several times more powerful than a common iron magnet of equal size. Although the projectile 21 is shown as being rectangular in shape, it is to be understood that it may be in any other suitable form such as square, round, triangular, or any other regular or irregular shape and may have any color desired.

The numeral 21 designates a projectile which is adapted to be thrown against the game board, in the playing of the game. The projectile 21 preferably is formed of relatively strongly magnetic material, such as for example "Alnico," a commercial alloy of aluminum, nickel, and cobalt which exhibits magnetic characteristics several

5 times more powerful than a common iron magnet of equal size. Although the projectile 21 is shown as being rectangular in shape, it is to be understood that it may be in any other suitable form such as square, round, triangular, or any other regular or irregular shape and may have any color used.

The numeral 21 designates a projectile which is adapted to be thrown against the game board, in the playing of the game. The projectile 21 preferably is formed of relatively strongly magnetic material, such as for example "Alnico," a commercial alloy of aluminum, nickel, and cobalt which exhibits magnetic characteristics several 15 times more powerful than a common iron magnet of equal size. Although the projectile 21 is shown as being rectangular in shape, it is to be understood that it may be in any other suitable form such as square, round, triangular, or any other regular or irregular shape and may have any color desired.

In the playing of the game, the game board 10 is set up and preferably inclined, as shown in Fig. 1, although it is to be understood that the panel 11 may be disposed in a vertical or horizontal plane or in any position desired. The object of the game is to throw one or more projectiles, such as 21, against the board 10 with the view of striking with the projectile or projectiles certain indicia or combinations thereof. Upon contact with the board, the projectiles are attracted to the metallic panel 11 and adhere to the board substantially at points where they strike. The projectiles are readily removable from the board for repeating the plays.

While the panel 11 is shown and described as being used in combination with an envelope, it is to be understood that it is also within the purview of my invention to provide a metallic panel of the character described upon which surface or surfaces game indicia are directly printed or lithographed, or a plastic member carrying the indicia may be bonded or suitably applied to the panel, or the panel may be mounted on a suitable frame. 45 Another modified embodiment would include a game board upon a surface of which was secured a plurality of magnetically attractive elements associated with game indicia.

I claim:

55 1. In a target game apparatus including a mag-

magnetic projectile, a target comprising a panel formed of magnetically attractable material and an envelope enclosing said panel and bearing game indicia at least on one face thereof, said envelope being open at one end to permit removal and insertion of said panel.

2. In a target game apparatus including a magnetic projectile, a target comprising a panel formed of magnetically attractable material and an envelope enclosing said panel and bearing game indicia at least on one face thereof, said envelope being open at one end to permit removal and insertion of said panel, and means for supporting said target in an inclined position.

3. In a target game apparatus including a magnetic projectile, a target comprising an envelope bearing game indicia at least on one face thereof, and a panel formed of magnetically attractable material removably received within said envelope and substantially coextensive in area therewith, said envelope being open at one end to permit removal and insertion of said panel.

5

veloppe and substantially coextensive in area therewith, said envelope being open at one end to permit removal and insertion of said panel.

IRVING H. FISHLOVE.
